(57) **CLAIM**

The ornamental design for a truck bed cap, as shown and described.

DESCRIPTION

FIG. 1 is a perspective view showing my new design of a truck bed cap;

FIG. 2 is a front plan view thereof;

FIG. 3 is a rear plan view thereof;

FIG. 4 is a right side plan view thereof;

FIG. 5 is a left side plan view thereof;

FIG. 6 is a top plan view thereof;

FIG. 7 is a bottom plan view thereof; and,

FIG. 8 is a front plan view thereof.

The broken line showing of environment is for illustrative purposes only and forms no part of the claimed design.
